COMBINATION LOCK

Antonín Kittler, Prague, Czechoslovakia

Application June 21, 1935, Serial No. 27,806
In Czechoslovakia February 8, 1935

1 Claim. (Cl. 70—310)

The subject of the invention is a combination lock of the kind in which several concentrically mounted tumblers are connected with sleeves which are slid into each other upon a shaft or a guide pin, these sleeves being divided by cross slots and their separated end portions being connected with a corresponding number of slotted discs arranged above each other, which discs have a considerable number of blind slots and a proper radial slot, which latter co-operates with a knife sliding together with the bolt.

The object of this invention is to prevent any alteration of the combination by an unauthorized person, and also to effect immediate closing of the door by the aid of a predetermined combination without setting the latter every time the door is closed, by merely sliding the bolt into the locking position by turning a knob arranged upon the shaft or pin, (or from the inside by operating an oscillating lever knob arranged upon the bolt,) so that the lock can be closed without using the combination from both sides and can also be opened from the inside without using the combination, but it can be opened from the outside only after setting up the combination. The lock, however, may, if required, be locked by simple means against opening from the inside without using the combination.

The invention also relates to a particular device for automatically displacing the tumblers as soon as, after the setting up of the combination, the lock has been opened or closed, without however cancelling the validity of the given combination for a new operation of the lock.

Instead of the sleeves which are slid upon each other, concentric, divided into two parts and in engagement with each other by edge teeth known per se, there may be used according to the invention with advantage undivided sleeves, the direct engagement of which with the tumblers can be cancelled.

In the drawings is illustrated a constructional example of the invention with appertaining details and modifications.

Fig. 1 shows a rear view i. e. a view from the inner side of the door upon the lock after removal of the front cover wall substantially in the section plane I—I of Fig. 2,

Fig. 2 is a horizontal section through the lock on line II—II of Fig. 1,

Fig. 3 is a top view of the bolt in the section plane III—III of Fig. 1,

Fig. 4 is a corresponding side view,

Fig. 5 is a detail of Fig. 2,

Fig. 6 is in horizontal section a modification of the construction according to Figs. 1 and 2,

Fig. 7 is a vertical section through a part of this arrangement on line VII—VII of Fig. 6,

Fig. 8 is a side view of the bolt omitting some parts of Fig. 6.

According to Figs. 1 to 4, the bolt 10 slides by turning the shaft 11 or the guide pin 11 and co-operation of the forked arm 12 of this shaft within the range of the arrow b—b with the pin 13 of the bolt 10 which latter is provided in its middle portion with a substantially rectangular recess 14 which on displacement of the bolt 10 into the open position 10' or back into the locking position according to Figs. 1 and 2, moves in transverse direction with regard to the shaft 11. 10

Upon the shaft 11 are loosely slid sleeves 15, 15', the number of which may be greater than two, and which carry the corresponding slotted discs 16, 16'. The discs are, according to the invention, constructed dish-shaped in the vicinity 15 of the hub, and are provided upon the periphery with an annular flange with false slots 17 and an effective radial recess 18 (Figs. 1 and 2). The dish-shaped portion of the slotted disc 16 arranged nearest to the bolt 10 is provided with a rearwardly projecting annular projection 16a, the object of which will be more fully described.

To a given number of dish-shaped discs 16 and 16' with corresponding sleeves 15 and 15' upon the pin 11, corresponds also the number of the dial rings 19, 19' upon the front side of the door, not counting the stationary dial ring 19a as the proper scale ring with letters, numerals or other stationary signs. The false slots 17 upon the periphery of the discs 16, 16' prevent in known manner ascertaining or feeling the correct recess 18 by the fence of the bolt 10. The fence of the bolt 10 consists in the illustrated constructional example of a narrow nose 24 of the double-armed oscillating lever 24 loaded by a spring 52, which is provided with a hand grip 25 and projects from the lock at the inner side of the door, that is, into the locked room. The lever 24 turns about the pivot 25'. This hand grip may, of course, be also omitted, or may be detachable if required, in order to prevent operation of the lock from the inside.

The longitudinal recess 14 in bolt 10 is provided at least upon one of its long sides with a flat projection 34 which possesses a shallow recess 20 with inclined end faces 20' which enable the slidable sleeve 15 to be depressed by means of its annular projection 16a upon slotted disc 16 of shaft 11 on insertion of the forked arms 21' of the yoke 21 (Figs. 2 and 5); the yoke is slidable at the inner side of the lock wall 26 and guided with its flat portion in the interspace between the wall 26 and the adjacent disc 16', and projects with the projection 21a from the opening 22 of the covering plate upon the small side 50 of the door wing 51. This displacing of the sleeve 15 with the disc 16 simultaneous with that of the remaining sleeve 15' and so on and discs 16' and so on, is rendered possible by setting the bolt 10 relatively to the shaft 11 into the correspond-

ing intermediate position 10" between the two end positions 10 and 10' (Fig. 1) of which the locking position with regard to the narrow end face 50 of the door wing 51 is illustrated by full lines in Fig. 1.

Only in this intermediate position (Figs. 3 and 4) can the sleeves 15 and 15' together with the slotted discs 16 and 16' be depressed (Fig. 4) and brought out of engagement with the teeth 58 of the upper sleeve parts 23, 23', which latter remain in their position in fixed connection with the dial rings 19, 19'. These rings can then be turned without hindrance for setting up a new combination, whereupon the lock can subsequently be locked or opened only under the new combination. The yoke 21 with the wedges 21' is shown in side view in Fig. 5.

If a new combination is to be set, the dial rings 19, 19' and so on and consequently the connected sleeves and discs must first be set in accordance with a previous combination in the open position of the door and the bolt entirely slid out, whereupon the bolt 10 is partly drawn back into the intermediate position 10" so that the fence 24' of the lever 24 of the bolt enters the correct slot 18 of the discs 16, 16'. In this position, the yoke 21 is slid with its wedges 21' between the fixed lock wall 26 and the opposite slotted disc 16', whereupon a new combination may be set, as the upper sleeve parts 23, 23' with the dial rings 19, 19' have by this means been brought out of engagement at 53 with the lower halves 15, 15' of the slotted discs 16, 16', which latter are still locked against rotation by the fence 24. The newly set combination is then valid from the moment of the complete closing or opening of the bolt 10 after previous removal of the wedge pair 21' by sliding back the yoke 21 into the originally illustrated position, as in these two end positions after 40 the sliding out of these wedges, both sleeve halves are again in engagement and the fence is outside the slot 18 of the discs 16, 16' both in its inner end position and in its outer end position (Fig. 2) with regard to the slotted periphery of the discs 16, 16'.

The fence 24 can be swung over in the direction of the arrow *a* (Fig. 2) by the operation of the hand grip 25 on sliding the bolt 10 from the inner side of the door, and this for the purpose of enabling the locked in person to open immediately the lock without using the combination. The oscillatable lever 24 with the nose 24' is turnable about a fixed pivot 25'. The other end of this lever terminates in a nose 21 (Fig. 2) which, on swinging over the fence prevents unauthorized removal of the sleeves 15, 15' from engagement with the upper sleeve parts 23, 23', that is, without knowledge of the old combination.

In order to prevent also opening of the lock 60 from the inside by operating the hand grip 25, for instance on leaving the apartment for a longer period, or the like, there is provided between the stationary lock wall 26' and the fence 24 an oscillatable lever 28 with a bent portion 29 which will lie opposite the fence when this lever 28 is turned into this locked position by hand before closing the door. In this case the proper combination must be set also on locking the door.

In order that on opening the lock after setting 70 the combination, the tumblers should automatically turn and thereby displace the set up but still

valid combination, there are provided upon the bolt 10 two projections 30 forming a fork between which extends the one arm 31' of a loop-shaped spring loosely turnable upon a fixed pivot 32 of the lock casing or the like, the free end 33 of this spring moving upon sliding of the bolt 10 within the range of the arrow *c-c* within the reach of the slotted discs 16, 16' in such a manner that upon its movement it co-operates every time with the slotted periphery and thereby automatically changes their original set position. This spring 31, 31' is for this purpose arcuate shaped and bent at an angle at the end 33. It is clear that this spring need not be arranged turnable upon the fixed pivot as a two-armed 15 spring lever, so that it can move with its free end in the already described manner in the reach of the slotted periphery of the discs 16, 16'.

In the constructional example according to Figs. 6 to 8, the inner end of the disc 16 is provided upon 20 its inner flange-like end with a segment shaped projection 35 which co-operates with the recess 36 of the bolt 10 and with an analogous recess 36' of the ring 38 of the disc 37, the ring enclosing the shaft 11. Between the inner disc 16 and the disc 37 is arranged a helical spring 39 which 25 permanently holds in engagement the discs 16, 16' and their lower sleeve parts 15, 15' with the corresponding upper sleeve halves 23, 23' in above described manner at the toothed separation plane 53. This engagement is also in this constructional example interrupted by the yoke 21 with the wedges 21' of Fig. 5. The segment-shaped projection 35 projects normally with its inclined end only into the recess 36' of the disc 37. If, however, the bolt 10 is slid into the previously described intermediate position, this projection 35 can penetrate still more deeply and into the recess 36 of the bolt 10, whereby setting 40 of a new combination is rendered possible. Sliding of the bolt is, of course, in this position, possible only if the original combination has been set, so that the right slots 18 of the discs 16, 16' are exactly above each other so that the nose 24' of the double armed lever 24 can be inserted into 45 them, said lever being in an analogous manner as in the previous example, arranged upon the inner side of the door. The recess 36 in the bolt is shown in side view in Fig. 8, from which may be also seen the arrangement of the bent double armed lever 24 with the nose 24'.

The remaining mode of operation of this combination lock according to Figs. 6 to 8 is identical with that of the lock according to Figs. 1 to 5. 55

What I claim is:

In a combination lock the combination of a bolt having two projections in the reach thereof, a casing, a spring pivoted to said casing, said spring having two arms, one of said arms engaging said bolt between said projections, a plurality of discs having a plurality of false slots and bolt releasing slots in the peripheries thereof, combination means for arranging said discs in a predetermined manner to permit movement of 60 said bolt, the other of said spring arms being adapted to engage said discs in said false slots to destroy the combination set up on said combination means after said bolt is moved. 65
